UNITED STATES PATENT OFFICE.

FREDERICK KOENIG, OF PITTSBURGH, PENNSYLVANIA.

FUEL-ARCH BREAKER FOR LOCOMOTIVE-STOKERS.

1,258,420.

Specification of Letters Patent.

Patented Mar. 5, 1918.

Application filed June 10, 1914. Serial No. 844,202.

To all whom it may concern:

Be it known that I, FREDERICK KOENIG, a citizen of the Republic of Switzerland, residing at Pittsburgh, in the county of Allegheny and State of Pennsylvania, have invented certain new and useful Improvements in Fuel-Arch Breakers for Locomotive-Stokers, of which the following is a specification.

10 The invention relates to mechanism for agitating the fuel used in automatic stokers for locomotives and has for its principal objects the provision of a simple and effective fuel agitating means whereby the fuel 15 in the locomotive tender is agitated in the vicinity of the discharge passage to prevent the formation of an arch which ordinarily forms above the passage and prevents the passage of fuel; the provision of a simple 20 operating mechanism for actuating the fuel agitator; the provision of a simple control mechanism for the fuel agitator, and such other objects as will hereinafter appear. Certain embodiments of the invention are 25 illustrated in the accompanying drawings, wherein—

Figure 1 is a central longitudinal section through the front portion of a locomotive tender such as is used with automatic stoker 30 mechanism for locomotives, showing the fuel agitator as applied for agitating the fuel above the discharge passage, and Fig. 2 is a diagrammatic sectional view of the valve controlling the fuel agitator operating mech- 35 anism.

Referring to Fig. 1, the principal part of the construction may be enumerated briefly as follows. 1 is a fuel receptacle in the front end of the locomotive tender, 2 is a discharge passage through which the fuel passes on its way to the locomotive fire-box (not shown), 3 is a coal crusher and distributor which reciprocates transversely of the passage 2, and is reciprocated by the link 4 connecting the crusher with a reciprocating driving rod 5 carried on the locomotive (not shown). 6 is a passage through the crusher into which the fuel from the receptacle 1 falls by gravity, 7 is a hopper into which the fuel in the crusher passage is discharged when the crusher is moved to rear portion, 8 is a transfer chute which receives coal from the hopper 7 and through which the fuel is moved forward by the reciprocation of the pivoted vanes 9. The fuel is eventually discharged from the chute

8 at the front end thereof into the stoker mechanism carried by the locomotive (not shown). The foregoing described apparatus is of the construction now in use in 60 automatic locomotive stokers and no claim is made to the novelty of such features, my invention relating to the mechanism for agitating the fuel above the discharge passage.

65 The arch breaker, or fuel agitating mechanism comprises an agitator arm 10 pivoted at 11 to the under side of the sloping rear wall 12 of the fuel receptacle 1. The arm is bent so that the end of the arm may project into the receptacle through the narrow slot 14 provided in the wall 12 to permit of the required motion of the arm. As shown, the arm 10 is in its lowermost position and the dotted outline of the arm indicates the extreme upper position. The motion of the arm agitates the coal in the vicinity above the discharge passage and breaks up any fuel arch that forms above the said passage.

70 The agitator arm is oscillated by means of the following mechanism. A compressed fluid cylinder 15 is secured to the partition wall 16, the said cylinder having therein a piston 17 connected to the piston rod 18. 75 To the end of the piston rod 18 is secured the guide head 19 which reciprocates in the guide 20 secured to the partition wall 16. A connecting rod 21 pivotally connects the guide head to the short end 22 of the agitator arm, therefore when the piston 17 is reciprocated by changes of fluid pressure on the faces of the piston, the agitator arm is oscillated into the positions shown.

80 The cylinder 15 is supplied with fluid 85 pressure from the auxiliary air reservoir 23, commonly carried on locomotive tenders, the air passing from the reservoir through the pipe 24 through the valve 25 and thence through either of the pipes 26 and 27 to the cylinder, pipe 26 leading from the valve to the lower end of the cylinder, while the pipe 27 leads from the valve to the upper end of the cylinder. The pipes 26 and 27 also serve as exhaust passages and the ports 90 through the valve are so arranged that when one pipe is serving as a supply pipe to the cylinder, the other is serving as an exhaust pipe 95 to the atmosphere.

100 Referring to Fig. 2 it will be seen that in 110 the position of the valve as shown in Figs. 1 and 2, air is passing through pipe 24, port

28 in the valve plug 29, through pipe 26 to the lower end of the cylinder, thus holding the piston up and the agitator arm in lowermost position, and at the same time air from the upper end of the cylinder is free to exhaust through pipe 27, port 30 in the valve plug and exhaust passage 31. If the valve plug 29 is shifted to the left or anticlockwise one quarter turn it will readily be seen that conditions will be reversed and air will pass from pipe 24 through port 28 into pipe 27 and thence to upper side of the piston, when the piston will be forced down, thus raising the agitator arm to extreme upper position, the air in the lower end of the cylinder being exhausted through pipe 26, port 30 to atmosphere through port 31.

It will be observed that by pivoting the 20 agitator arm outside the receptacle 1, all operating parts are free from contact with the fuel with the exception of the end 13 of the agitator arm, and therefore there is no obstruction offered to the operative parts by 25 the fuel, and all parts may be readily inspected and repaired at any time. The slot 14 in the wall 12 is cut directly above the hopper 7, so that fuel sifting through the slot falls into the hopper 7 and is not wasted.

The operation of the mechanism is as follows: When fuel ceases to pass through the chute 8 it is an indication that the fuel has become arched above the passage into the 35 chute. When such a condition arises the operator moves the valve handle 32 to the left causing the piston 17 to be forced down and the agitator arm to be forced up, thereby agitating the coal above the passage 2 and breaking the arch so that coal will again 40 freely pass through the passage. A continued oscillation of the agitator arm is caused by moving the valve handle 32 back and forth until the desired effect is produced.

45 It is quite obvious that valve mechanism could be employed that would cause the piston 17 to reciprocate continuously as long as air was supplied to the cylinder, in which event the operator would be required to 50 open a valve to operate the piston and leave

such valve open as long as oscillation of the agitator arm was considered necessary. Other modifications of construction might be made without departing from the spirit of my invention.

55

What I claim is:

1. The combination with a fuel receptacle having a discharge opening through its lower side, a closure means for the opening and an inclined wall extending upwardly and to the rear from said opening and provided with a slot, a V-shaped agitator pivoted at one end to the inclined wall and provided at such end with an operating lever and having its other end working through said slot, and means for swinging the agitator about its pivot independently of the actuation of the said closure means, the said agitator being mounted so that its agitating arm in its upward movement 70 swings longitudinally of the inclined wall and away from said wall.

2. The combination with a fuel receptacle having a discharge opening through its lower side, a closure means for the opening and an inclined wall extending upwardly and to the rear from said opening and provided with a slot, a V-shaped agitator pivoted at one end to the inclined wall and provided at such end with an operating lever and having its other end working through said slot, and means for swinging the agitator about its pivot independently of the actuation of the said closure means, the said agitator being mounted so that its agitating arm in its upward movement 75 swings longitudinally of the inclined wall and away from said wall, and the said agitator being formed from a flat metal plate working edgewise and having its working 80 edge at substantially right angles to the center line of the V-shape in which the agitator is formed.

In testimony whereof I have hereunto signed my name in the presence of the two 95 subscribed witnesses.

FREDERICK KOENIG.
